UNITED STATES PATENT OFFICE.

ROBERT J. McLANAHAN, OF WOODLAWN, PENNSYLVANIA.

WATER CLOSET.

Application filed May 22, 1922. Serial No. 562,620.

To all whom it may concern:

Be it known that I, ROBERT J. McLANAHAN, residing at Woodlawn, in the county of Beaver, and State of Pennsylvania, a citizen of the United States, have invented or discovered certain new and useful Improvements in Water Closets, of which improvements the following is a specification.

My invention relates to improvements in water closets and consists in means for inducing a ventilating current of air to flow from the bowl to a ventilating pipe, so long as the bowl is in use. The object is to carry away gases.

The invention is illustrated in the accompanying drawings. Fig. I is a view in side elevation of a water closet, having applied to it the means and instrumentalities wherein my invention is found; Fig. II is a fragmentary view in plan from above, the seat being removed; Fig. III is a view in vertical section and to larger scale, on the plane indicated by the line III-III, Fig. I; and Fig. IV is a view in vertical section of the same portion of the structure as shown in Fig. III, but on a plane of section at right angles to that of Fig. III.

The familiar parts of the water closet will immediately be recognized: the bowl 1, seat 2, tank 3, and flushing pipe 4. I provide additionally a ventilating pipe 5, a nozzle 6, a valve 7, and operating means and ancillary devices.

In intervals between successive flushings, the flushing pipe 4 of the water closet is empty. It enters the bowl horizontally, or substantially so, at the upper rim and from the rear, and affords a suitable passage through which I accomplish the desired ventilation. It will of course be understood that another passageway might be provided.

The ventilating pipe 5 as here arranged leads from a horizontal reach of flushing pipe 4, and leads vertically downward, and, as will be understood, leads to a suitable place of gas delivery. The particular positions, relative to the vertical, here noted are not essential, but are convenient.

Communication from flushing pipe 4 through ventilation pipe 5 is normally cut off by valve 7, and accordingly a valve casing 8 is introduced at an intermediate point in the extent of flushing pipe 4, and within this casing valve 7 functions. Normally, as I

have said, the valve is closed, and passage through the flushing pipe from tank 3 to bowl 1 is continuous, so that on the opening of the tank the flushing charge of water may pour into the bowl in full and unbroken stream. As here shown, the valve moves vertically and rests of its own weight normally in closed position, and after being opened returns under gravity, when free to do so, to closed position.

Fig. IV shows the valve 7 in inactive, normal and closed position. The valve is essentially a disk with depending marginal flange, adapted to close cap like upon the upstanding end of ventilating pipe 5. The upper end of pipe 5 is encircled, within casing 8 with a channel or trough, and into this trough the marginal flange of valve 7 extends, when the valve is down. When the valve is raised, the marginal flange upon valve 7 rises from the channel or trough. The channel or trough is exposed to the flushing stream through pipe 4, and is thus in service kept supplied with a sealing pool of water.

It will be understood that the valve when closed prevents any diversion of water from the flushing stream save only an inconsiderable leakage, which it is not necessary nor desirable to prevent; that after flushing, while the valve continues closed, leakage will permit the flowing away of water from the valve casing 8 through pipe 5, until there remains only the sealing pool in the channel or trough surrounding the upper end of pipe 5; and that when subsequently the valve 7 is raised and the liquid seal broken (pipe 4 being at the time empty, so far as the flushing stream is concerned) a way will be opened for a ventilating stream of air from the bowl through the adjacent end of pipe 4, under the valve 7 and through ventilating pipe 5.

Within pipe 5, beneath valve 7, and conveniently adjacent valve 7, are arranged means for inducing a flow of air from the bowl through pipe 5. These means include essentially the nozzle 6 adapted to project a jet of fluid into pipe 5 in direction such as to induce the desired flow downward, as here shown. The fluid employed may be such as desired, but conveniently it will be water from the water supply and under the head which obtains; and, accordingly, the nozzle 6 is here shown to be fed from the supply pipe 9 which leads also to tank 3. A control

valve in a suitable casing 10 stands normally closed, but at suitable time is opened to allow water under pressure to flow to nozzle 6 and to be projected from the nozzle in a jet. The nozzle may in its minute construction be such as desired; I have indicated a nozzle including two relatively rotary members—a familiar construction. By relative turning the orifice may be enlarged and diminished and modified in shape, to project a jet varying in shape and in force.

The jet 6 is preferably arranged centrally within pipe 5, delivering its jet axially downward. Associated with the jet I find it advantageous to place within pipe 5 a Venturi tube 11, into which the jet is immediately projected. The presence of the Venturi tube increases the suction, or inductive effect.

Nozzle 6 may be carried on a bridge 12, and this bridge with its nozzle and pipe connection, together with the Venturi tube, may be made up as an integral fitting, adapted to be introduced intermediately in the exit 25 tent of pipe 5, all as clearly indicated in Figs. III and IV.

The air valve 7 in casing 8 and the water valve in casing 10, both stand normally closed. When both are open, the jet of water projected from nozzle 6 induces a ventilating stream of air from the bowl through pipe 5.

The water closet seat 2 constitutes one end of a beam pivoted at 13; the opposite end of the beam extends rearward at an arm 14. A spring 15 engaging this beam holds it normally in such position that the seat is slightly raised, standing in such position as is indicated in Fig. I. When a user sits upon the seat his weight overcomes the resistance of the spring and swings the beam (depressing the seat) through a slight but sufficient swing (anticlockwise upon pivot 13, as illustrated in Fig. I). The upward swing of arm 14 is sufficient, through suitable connections sufficiently illustrated in the drawings and requiring no minute enumeration, to open both valves. The connections are advantageously so adjusted that the 50 valve within casing 10 opens first; so that

the jet from nozzle 6 is already exerting its flow-inducing influence when the valve 7, breaking its seal, opens. When the user leaves the seat, the tension of spring 15 is effective to swing the beam again in opposite direction (clockwise on pivot 13), allowing the two valves to seat themselves again, preferably in inverse order—first valve 7, then the valve controlling the flow of water to nozzle 6.

Operation may be briefly summarized: When the user seats himself, his weight effects automatic opening of the two valves, and so long as he remains seated a ventilating stream of air will flow from the bowl 65 through the proximate end of pipe 4, and thence through pipe 5 carrying with it objectionable gases. When the user leaves the seat the valves will close and the pipe 4 will then be in condition to carry the flushing 70 stream from tank to bowl. The repeated flow of the flushing stream maintains the sealing pool into which the peripheral flange upon valve 7 normally dips and from which it rises to open the pathway for the flow of 75 the ventilating stream of air.

I claim as my invention:

In a water-closet installation the combination with a bowl and a flushing pipe opening horizontally thereto, a ventilating pipe 80 opening vertically from the horizontal reach of the flushing pipe and surrounded at its upper end with a water-receiving channel, a valve with flanged periphery adapted to move vertically above the upper end of the 85 ventilating pipe and by the dipping of its flange into and rising out from a body of water maintained in said channel alternately closing and opening communication from flushing pipe to ventilating pipe, 90 means for raising said valve, and a fluid-supply pipe terminating in a nozzle within the ventilating pipe and at a point in the induced stream beyond said flanged valve.

In testimony whereof I have hereunto set 95 my hand.

ROBERT J. McLANAHAN.
